US00D606928S

(12) **United States Design Patent**
Song

(10) **Patent No.:** US D606,928 S
(45) **Date of Patent:** ** Dec. 29, 2009

(54) **TIRE**

(75) Inventor: **Wenguang Song**, Dongying (CN)

(73) Assignee: **Xingyuan Tyre Group Co., Ltd.**,
Dongying (CN)

(**) Term: **14 Years**

(21) Appl. No.: **29/283,311**

(22) Filed: **Aug. 10, 2007**

(30) **Foreign Application Priority Data**

Jun. 19, 2007 (CN) 2007 3 0158984

(51) **LOC (9) Cl.** **12-15**

(52) **U.S. Cl.** **D12/579**; D12/901

(58) **Field of Classification Search** D12/500-502,
